TELESCOPING LINKAGE HAVING DETACHABLE LINKS WITH CLOSED EDGES

August Pfisterer, Jr., Pforzheim, Germany, assignor to August Pfisterer Jr., K.G., Pforzheim, Germany

Filed Nov. 2, 1959, Ser. No. 850,450

Claims priority, application Germany Nov. 3, 1958

4 Claims. (Cl. 59—79)

The present invention relates to expandable link straps, and more specifically to an expandable link strap for wrist watches and the like, which comprises a series of links the longitudinal axes of which extend in the transverse direction of the strap, each of said links being comprised of a pair of box-like link elements including an outer decorative link element and a similar intermediate link element slidable within said outer decorative link element.

Expandable link straps of this type have already become known which comprise decorative link elements with open adjacent sides from which laterally open intermediate link elements can be partially withdrawn, said intermediate link elements having a longitudinally slotted bottom engaged by a lug provided in one of the open sides of the decorative link elements. The lug compresses a spring, located inside the intermediate link element between between the lug in the decorative link element and one transverse wall of the intermediate link element, when the strap is expanded, and urges the intermediate link element back into the decorative link element when the tension on the strap is relaxed, thus causing the expanded strap to contract.

It is a drawback of such straps that it is possible to see through the open ends of the intermediate link elements when the strap is expanded. Apart from imparting to the strap a general appearance of hollowness and fragility, this form of construction actually facilitates buckling and deformation because of the absence of end walls. It would be quite possible to form end walls on such intermediate link elements, but this would gravely interfere with the work of assembling the link elements, since the springs must be in position before the intermediate link elements can be connected. In practice this would be difficult to effect and increase the cost of production.

It is the object of the present invention to overcome this drawback and at the same time offer a satisfactory solution of the problem of simplifying the work of assembly.

An important feature of the invention consists in that part of the material to be stamped out of the bottom wall of the intermediate link element for forming the longitudinal slots is left connected with the bottom wall and is bent inwardly near the strap edges to form guide walls adapted to locate the compression spring between them, an opening being provided in one transverse wall of each intermediate link element for the introduction therethrough of the spring, and a cross plate serving to close said opening and retain the spring when the strap is expanded. In this form of construction it is impossible to see through the intermediate link elements, and the guide walls prevent the intermediate link elements from buckling when they are squeezed. Moreover, after the springs have been inserted into the intermediate link elements unskilled labour can be employed to connect the link elements together without using tools, and the production

2

of the completely closed intermediate link elements is therefore cheap.

A preferred embodiment of the invention will now be described by way of example and with reference to the accompanying drawing in which:

Fig. 1 is a top plan view, partly in section, of a portion of an expandable link strap according to the invention, some strap links being shown in expanded and some in contracted position;

Fig. 2 is a side view of a portion of the strap, likewise showing some links in expanded and some in contracted position;

Fig. 3 is a perspective view of a link in expanded position, said link being comprised of a pair of box-like link elements including an outer decorative link element and a similarly intermediate link element;

Fig. 4 is a similar view of an inverted intermediate link element, and

Fig. 5 is a similar view of a cross plate.

As shown in Fig. 1, an expandable link strap according to the invention comprises a series of links the longitudinal axes of which extend in the transverse direction of the strap, each of said links being comprised of a pair of box-like link elements including an outer decorative link element A and a similar intermediate link element B slidable within said outer decorative link element.

Each of the decorative link elements A has a top wall 2', a bottom wall 2, end walls 9 and open transverse sides 1 and 1'. At the transverse side 1 the bottom wall 2 of the link element A is formed with two spaced lugs 3 which are bent perpendicularly upright. The intermediate link elements B are inserted into the decorative link elements A from the side 1' which is opposite the side 1 formed with said lugs 3. Each of the intermediate link elements B has a top wall 4', a bottom wall 4, a rounded transverse wall 11, a straight transverse wall 12 and longitudinal slots 5 formed in the bottom wall 4 and spaced the same distance apart as said lugs 3 so that the slots 5 are engageable by the lugs 3. A compression spring 6 contained inside the intermediate link element B is held by said lugs 3 and is therefore compressed if the intermediate link element B is partially withdrawn from the link element A. The portion of the intermediate link element B which projects from the side 1 of link element A is fastened to the adjacent decorative link element A by means of a snap-action link pin 7 which is pushed crosswise through the intermediate link element B, and which has inwardly yielding pin ends 7' insertable into holes 8 in the end walls 9 of the adjacent decorative link element A.

The longitudinal slots 5 in the bottom wall 4 of the intermediate link element B for engaging the lugs 3 of the cooperating decorative link element A are stamped out in such a way that parts of the material removed from the bottom wall 4 remain connected nearest the strap margins with the material forming the bottom wall 4 of the intermediate link element B and are then bent perpendicularly inwardly into the inside of the intermediate link element B so as to form guide walls 10 for the compression spring 6. The guide walls 10 are shorter than the length of the slots 5 and do not extend into the rounded transverse wall 11, nor do they extend to the straight transverse wall 12 of the intermediate link element B. However, the slots do extend about half way into the rounded transverse wall 11. Lateral lugs 13 are formed on the straight transverse wall 12 and are bent over the edge of the bottom wall 4 of the intermediate link element which at these places is provided with cooperating depressed edge portions 14 so that the lugs 13 lie flush with the general surface of the bottom wall 4 (Fig. 4). The straight transverse wall 12 has an opening 15 with ends

15' and of a width corresponding with the distance between the two guide walls 10. The compression spring 6 can thus be inserted into the intermediate link element B through said opening 15 and will then be guided by the two guide walls 10. After insertion of the compression spring 6, the opening 15 is closed in that a cross plate 16 (Fig. 5) is slidably placed across said opening 15. As shown in Fig. 4, the guide walls 10 have cut ends 10' and 10'' and said cross plate 16 is inserted between the cut ends 10' of the guide walls 10 and the straight transverse wall 12 of the intermediate link element B. The cross plate 16 has a central offset portion 17 between shoulders 17'. The central offset portion 17 has a length equal to that of the opening 15 in the straight transverse wall 12 and engages said opening 15, the shoulders 17' bearing against the ends 15' of the opening 15 and thereby preventing the cross plate 16 from shifting after it has been correctly inserted. The particular conformation of the cross plate 16 does not therefore reduce the available withdrawal of the intermediate link element B from the link element A by introducing an additional thickness of the material, and the compression spring 6 is at the same time located by a recess formed by the offset portion 17 of the cross plate 16.

The intermediate link element B can then be readily inserted into the decorative link element A from the open transverse side 1' thereof and pushed through the same, as shown in Fig. 3. In this position the link pin 7 can be pushed through the intermediate link element B and between the rounded transverse wall 11 and the cut ends 10'' of the guide walls 10, and connected with the adjacent decorative link element A.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description and all changes which come within the meaning and range of equivalency of the claims are therefore intended to be 40 embraced therein.

I claim:

1. An expandable link strap for wrist watches and the like comprising a series of links the longitudinal axes of which extend in the transverse direction of the strap, each of said links being comprised of a pair of box-like link elements including an outer decorative link element with a top wall, a bottom wall, end walls and open transverse sides and a similar intermediate link element slidable within said outer decorative link element and having a top wall, a bottom wall, a rounded transverse wall and a straight transverse wall, two spaced lugs formed on the bottom wall at one of the open transverse sides of the outer decorative link element and projecting perpendicularly upright from said bottom wall, two spaced slots extending with parallel longitudinal outer and inner edges in the bottom wall of the intermediate link element in the longitudinal direction thereof and engaged by said lugs, guide walls formed integral with the bottom wall of the intermediate link element and projecting perpendicularly from the outer longitudinal edges of the slots into the intermediate link element, an opening provided in the straight transverse wall of the intermediate link element, a removable cross plate for closing said opening, and a compression spring in said intermediate link element, guided by said guide walls and adapted to be compressed by the lugs upon expansion of the strap.

2. An expandable link strap for wrist watches and the like comprising a series of links the longitudinal axes of which extend in the transverse direction of the strap, each of said links being comprised of a pair of box-like link elements including an outer decorative link element with a top wall, a bottom wall, end walls and open transverse sides and a similar intermediate link element slidable within said outer decorative link element and having a top wall, a bottom wall, a rounded transverse wall and a straight transverse wall, two spaced lugs formed on the bottom wall at one of the open transverse sides of the outer decorative link element and projecting perpendicularly upright from said bottom wall, two spaced slots extending with parallel longitudinal outer and inner edges in the bottom wall and half way into the rounded transverse wall of the intermediate link element in the longitudinal direction thereof and engaged by said lugs, guide walls formed integral with the bottom wall of the intermediate link element and projecting perpendicularly from part of the outer longitudinal edges of the slots into the intermediate link element, an opening provided in the straight transverse wall of the intermediate link element, a removable cross plate for closing said opening, and a compression spring in said intermediate link element, guided by said guide walls and adapted to be compressed by the lugs upon expansion of the strap.

3. An expandable link strap for wrist watches and the like comprising a series of links the longitudinal axes of which extend in the transverse direction of the strap, each of said links being comprised of a pair of box-like link elements including an outer decorative link element with a top wall, a bottom wall, end walls and open transverse sides and a similar intermediate link element slidable within said outer decorative link element and having a top wall, a bottom wall, a rounded transverse wall and a straight transverse wall, two spaced lugs formed on the bottom wall at one of the open transverse sides of the outer decorative link element and projecting perpendicularly upright from said bottom wall, two spaced slots extending with parallel longitudinal outer and inner edges in the bottom wall and half way into the rounded transverse wall of the intermediate link element in the longitudinal direction thereof and engaged by said lugs, guide walls formed integral with the bottom wall of the intermediate link element and projecting perpendicularly from part of the outer longitudinal edges of the slots into the intermediate link element, an opening provided in the straight transverse wall of the intermediate link element, a removable cross plate for closing said opening and disposed between the straight transverse wall with its opening and the relative ends of the guide walls, said cross plate being formed with a central offset portion defined by shoulders which fit into said opening, and a compression spring in said intermediate link element, guided by said guide walls and adapted to be compressed by the lugs upon expansion of the strap.

4. An expandable link strap as claimed in claim 2, wherein a snap-action link pin is inserted between the rounded transverse wall of the intermediate link element and the relative ends of the guide walls and the yielding pin ends are insertable into corresponding holes in the adjacent decorative link element for articulating the intermediate link element with said decorative link element.
